CONSTRUCTION AND ARRANGEMENT OF
AEROPLANE WINGS

James Martin, Higher Denham, England

Application July 15, 1933, Serial No. 680,541
In Great Britain July 20, 1932

4 Claims. (Cl. 244—12)

This invention comprises improvements in and connected with the construction and arrangement of aeroplane wings of the kind in which each wing is provided with a main spar composed of 5 three longitudinal main members arranged triangular section, and it has for its object to provide a construction and arrangement of aeroplane wing which will be both light and strong and capable of readily standing all the stresses to 10 which it may be subjected. A further object is to provide a simple method by which the wings or suitable portions of them may be folded back so as to occupy a minimum of space and without in any way fouling or interfering with the tail plane 15 or other parts of the machine. A still further object is to provide an improved arrangement of struts and stays for the three main longitudinal members of each wing with improved means for detachably securing such struts and stays to the 20 longitudinal members. The invention may also be arranged to enable the wing spar to pass completely through or across the fuselage or body of the aeroplane without interfering with the accommodations for the passengers or pilot.

25 In carrying one embodiment of the invention into practice I employ a cantilever type of single-spar wing in which a single lattice girder spar of substantially triangular section is arranged in each wing. The triangular lattice girder spar extends along the length of the wing and is arranged at or near the centre of pressure of the wing throughout its length. The triangular lattice girder is constructed of a series of longitudinal members connected together by suitable 30 struts and stays across its three faces and the strength and disposition of the longitudinal members and the struts and stays forming the triangular lattice girder are such as to effectively stand up to the loads and stresses throughout the whole 35 length of the spar. The size or thickness of the longitudinal members may vary, being preferably reduced toward the outer ends of the spar and the members may themselves converge toward the wing tip so that the effective dimensions of 40 the triangular lattice girder spar tapers from the root to the wing tip. The struts are arranged in such a manner that they form a series of substantially closed triangles round the three faces of the spars with the ends of the struts substantially 45 normal to the longitudinal members. The stays are disposed diagonally across the struts, the stays at each face of the spar being substantially parallel to each other.

50 In order that my invention may be clearly understood and readily carried into effect I have 55

appended hereto three sheets of drawings illustrating embodiments thereof and wherein:—

Fig. 1 is a broken perspective view showing the triangular section spar secured to and carried through the fuselage frame to provide an arrangement in which the spar allows for space for accommodation of a pilot or passenger. 5

Fig. 2 is a detail side elevation view showing how such space is made use of.

Fig. 3 is a detail plan view showing a suitable 10 method of locking the outer foldable section of a wing spar in position for flights.

Fig. 4 is a sectional side elevation view showing a suitable form of locking device for obtaining an easy positive locking of the inner and outer 15 sections and an easy unlocking action.

Fig. 5 is a detail sectional end elevation view of the spar showing the preferred form of strutting.

Fig. 6 is a diagrammatic side elevation view 20 showing how the spar is related to the fuselage and wings in a monoplane.

Fig. 7 is a diagrammatic side elevation view showing how the angle of incidence of the wing 25 may be adjusted relatively to the fuselage.

Figs. 8, 9 and 10 are diagrammatic front elevation views showing different arrangements of the stub or central section of a pair of wings, and

Figs. 11, 12 and 13 are diagrammatic views showing suitable arrangement of the struts and 30 stays on the three faces of the triangular spar.

Referring to the drawings the embodiments shown are of a main spar in the form of what I term a triangular section lattice girder which 35 preferably comprises three steel tubular longitudinal members 1, 2 and 3 disposed at the three corners of the triangle and extending laterally from the fuselage or body of the aeroplane the frame of which is indicated generally by the reference numeral 4. These tubular longitudinal members 1, 2 and 3 of the spar are preferably 40 solid drawn circular steel tubes of the desired size and strength. Where it is necessary to join the tubes the ends may be butted together and connection made by means of an internal or external sleeve or both, the parts being suitably secured together in any convenient manner or in accordance with the manner described in my prior Patent No. 1,867,226. The disposition of 45 the longitudinal members of the triangular spar are preferably such that the spar is located at or near the centre of pressure of the wing section as shown in Fig. 6 which also usually corresponds substantially with the greatest depth of the wing.

The longitudinal members are preferably ar- 50 55

ranged so that two of them indicated by the reference numerals 2 and 3, are located vertically or nearly vertically one above the other whilst the third longitudinal member 1 is arranged in 5 front of these two longitudinal members 2 and 3 and preferably at or slightly above the normal level of the lower member 3 of the two rear longitudinal members. The three longitudinal members of the triangular spar are connected to 10 together on each of the three faces of the spar by a suitable system of struts and stays 5 in the form of tubular steel struts or stays 5 as shown in Fig. 1, the arrangement comprising a series of struts 5 arranged at intervals along the length 15 of the spar so that they are arranged in a series of three struts 5a, 5b and 5c (see Fig. 5) forming a substantially closed triangle round the three faces of the spar. Each series of such struts 5 are separated from each other by a suitable 20 distance forming "bays" across which a series of diagonal stays 6 extend from the corners of each series of struts to the nearest series of struts, the direction of the diagonal stays at each face of the spar being substantially parallel 25 to each other. Each face of the spar may thus comprise two longitudinal members for example 1 and 2 connected together at intervals by a series of struts 5 arranged so that their ends are substantially normal to the longitudinal members 30 and connected together by diagonal stays 6. The struts 5 and stays 6 are secured to the longitudinal members 1, 2 and 3 by suitable clamping means preferably substantially in the manner described hereafter. The struts 5 and 35 stays 6 preferably comprise suitable solid drawn tubes of steel or other suitable material as shown in Figs. 1 and 5 the ends of which are flattened out as at 7 and reinforced to provide eyes having holes drilled or otherwise formed therein to fit 40 accurately over a suitable screw-threaded stud 8. The eyes are preferably formed in the end of the tubular struts and stays by inserting a tubular liner in the ends and subsequently pressing or flattening the ends to form the eye. The open 45 ends of the flattened eye and preferably a portion along the edge thereof are welded together so that the tube and the reinforcing insert are positively connected together so as to make the total strength of the eye after the formation of 50 the hole therein equal to or even greater than the strength of the strut or stay itself. The struts and stays are preferably formed to definite pre-arranged lengths and may be suitably numbered or marked to denote their position in the spar. 55 The said eyes which receive the studs 8 are preferably drilled in suitable jigs so as to ensure accuracy within fine limits thus enabling rapid assembly and also permitting the quick interchange and replacement of any strut or stay. The struts and stays are clamped to the longitudinal tubular members 1, 2 and 3 by means of sheet metal or tubular inserts 10 (see Fig. 5) placed inside the longitudinal members at the position where the struts and stays are to be clamped. Each 60 such metal insert may comprise a ring or part ring of steel or other suitable material adapted to fit closely within the bore of the longitudinal member 1, 2 or 3 into which it is placed and provided with screw-threaded nuts 11 brazed, welded 65 or otherwise permanently secured to its inner face at the desired positions. Each metal insert may thus comprise a substantially C-shape circular ring or part ring of metal having two screw-threaded nuts 11 as shown in Fig. 5 which may 70 be conical in shape welded, brazed or otherwise 75

secured to their inner face. The longitudinal tubular members of the spar are drilled at the desired positions and the screw-threaded studs or set-screws are passed through these holes and screwed into the nuts on the metal inserts 5 so as to be firmly held therein. Each stud is provided with a plain portion or shank over which is placed a saddle washer 12 curved or otherwise shaped on its inner face to correspond with the outer face of the tubular longitudinal member 10 of the spar. Over each stud is then placed the eye of a strut 5 and also over some a stay 6 and these are clamped in position by means of a suitable nut 13 screwed onto the outer end of the stud. The plain shank of the stud is preferably of such a length as to provide a plain bearing surface for the hole in the eyes of both the strut and the stay but the screw-thread on the end of the stud extends slightly into the outer stay so as to ensure that the clamping nut 15 may be drawn up tight. If desired the clamping nut may be slightly recessed on its inner face for this purpose. The nut may be castellated so as to enable it to be locked in position by means of a split pin or wire passed through a perforation in 20 the stud and through the recesses in the end of the nut. Any other suitable means may be employed for locking the nut on the stud.

The triangular lattice girder forming the spar of the wing may be anchored to suitable parts of 30 the fuselage or to the body or frame of the aeroplane or to the ends of a stub section 14 of wing built into the fuselage 4. In the latter case the stub section of wing may be provided with a section of triangular lattice girder corresponding 35 to the spar and the longitudinals 1a, 2a and 3a of which may extend right through the fuselage as shown in Fig. 1. The longitudinal members may be anchored or secured to suitable portions of the fuselage or frame and the centre section 40 of the lattice girder where it extends across the fuselage may have some or all of the diagonal stays omitted as indicated at 15 in Fig. 1 or so arranged that they will not cause an obstruction 45 in the interior of the fuselage. By this means one or more of the seats 16 for passengers or pilot may be actually located within the triangular lattice girder as shown in Fig. 2. This enables the over-all height of the cock-pit or 50 pilot's or passengers' compartment to be kept down to a minimum whilst affording ample head room and also it enables a pilot or passenger in rear of the seat or seats 16 to find leg room within the stub section 14.

When it is desired to arrange the wings to 55 fold back along the side of the fuselage, the triangular lattice girder spar may be made to hinge at the ends of two of its longitudinal members. For this purpose the spar may be hinged to the end of a short stub section 14 of wing having 60 a triangular lattice girder spar corresponding to the lattice girder spar in the folding section of each wing. The two rear longitudinal members 2 and 3 and 2a and 3a both of the spar and the lattice girder in the stub section are provided with suitable plugs 11 fixed into their ends and these plugs are arranged with interlocking tongue and forked hinge members 18 and 19 respectively through which a suitable pivot pin 20 is passed and the pivot pin of the tongue and 65 forked members in the upper and lower longitudinal members are arranged in line with each other so as to form a common axis about which the spar may pivot. This axis may either be 70 vertical or inclined in a forward or rearward 75

direction so that when the folding section of the wing is turned round about this axis the wing tip will clear the tail plane or any stays or struts connected thereto. The forward longitudinal members 1 and 1a in the wing spar and the stub section are provided one with a tapered or conical plug 21 preferably fixed in the ends of the member 1 as shown in Fig. 3 and the other with a correspondingly shaped socket 22 adapted to fit closely one into the other member 1a when the folding wing is opened out to the flying position. A suitable locking bolt or any other desired safety locking device is provided to enable the ends of the two portions of the forward longitudinal member to be positively and definitely secured together. One method may consist in passing a suitable tapered pin 23 which may be threaded through an aperture 24 passing through both the conical plug and the socket in which it engages. A safety spring catch or other device may be provided to retain the taper pin in position, the taper pin being attached to some fixed part by means of a short chain or other flexible connection to prevent it from becoming lost. However it is preferred to adopt the locking device shown in Fig. 4 in which the pin 23 is threaded as at 25 intermediate its ends in a sleeve 26 extending integrally from the socket 22 or a collar 27 fixed to the tube 1. The pin 23 is advanced through the aperture 24 or retracted therefrom by rotating it preferably by means of a handle 28 permanently connected in substantially axial alignment to the pin 23 by a universal coupling 29. This handle 28 rotates in a bearing 30 in the outer end of a tubular casing 31 fixed at its inner end to the sleeve 26, and a collar 32 on the handle limits the axial travel of the pin 23 outwards, whilst a flange 33 limits its movement inwards. The sleeve 26 can be of gunmetal or brass and the casing 31 of a cheaper and lighter metal, the front end of the casing 31 being supported in the front edge of the wing.

If desired the wing spar may be mounted adjustably so as to enable the angle of incidence of the wing to be altered at will. For this purpose the triangular lattice girder of the stub section or wing spar may be mounted in suitable supports on the fuselage or frame of the aeroplane so that it may hinge or turn about one of the longitudinal tubular members of the triangular lattice girder. It is preferred that the lattice girder should hinge about either the lower or upper of the rearward longitudinal members 2 and 3 of the triangular lattice girder spar whilst the angular adjustment should be effected by adjustably anchoring the forward longitudinal member 1. For example as shown in Fig. 7 the wing hinges on the lower rear member 3, and the third longitudinal member 1 may pass through slotted plates or brackets the slot being of an arcuate form the centre of which corresponds with the axis of the tubular member 3 about which the triangular lattice girder hinges. The adjustment may be effected by suitable screw or other means adapted to raise or lower the forward longitudinal member of the triangular lattice girder. Suitable locking means may be provided to secure the lattice girder in any adjusted position. If desired means may be provided to enable the adjustment to be effected whilst the aeroplane is in flight thus enabling the angle of incidence of the wing to be adjusted to the conditions of flight, so that the wing may be set at a greater angle of inci-

dence when taking off or landing and to a lesser angle of incidence when in normal flight or when flying "light".

Where the wings are arranged to fold back along the side of the fuselage it is desirable to arrange a short length of the trailing edge of the wing to fold up so as to permit the wing to lie close alongside of the fuselage as shown in Fig. 6. For this purpose a sufficient length of the trailing edge of the wing may be arranged to hinge about the upper rear longitudinal member of the triangular spar as indicated by the reference 1d. When the wing is opened out into the flying position this section of the trailing edge is turned down into its normal position for flight and is firmly secured against the rear face of the triangular spar. Any suitable locking means may be provided to secure the framework of this portion of the trailing edge to the lower rear longitudinal member of the triangular spar. One method may consist in providing suitable inter-engaging tongue and socket members adapted to fit one in the other when the trailing edge is in the flying position and providing suitable spring or other catches to engage and lock them in position. For this purpose suitable spring bolts or latches may be employed at intervals along the length of the foldable trailing edge of the wing and these bolts or latches may be interconnected by a rod cable or other connecting means so that they may be disengaged at one operation when it is desired to fold back the section of trailing edge. Suitable struts 38 (see Fig. 6) or other means may be provided to secure the folding trailing edge in the raised position whilst the wing is being folded back or opened out.

My improved construction and arrangement of aeroplane wing and spar is particularly adapted for use in connection with the cantilever type of wings for mono-planes and is so arranged that it is possible to dispense with all bracing to the wing spar other than the struts and stays which form fixed parts of the spars. The invention may however, be employed in connection with bi-planes or aeroplanes having more than two planes and if desired suitable inter-connecting struts and bracing or other external bracing may be employed where desired.

The main tubular members 1, 2 and 3 may be bolted to the fuselage frame by forming flanges 34 on both at the appropriate points and passing the bolts through the flanges, such flanges preferably being formed at corners of the frame work of the fuselage as shown in Fig. 1 as regards the lower members 1 and 3. Where such flanges are not at corners as shown with the upper member 2 it is prepared to diagonally strut such flanges with others as indicated by the struts 35 in Fig. 1.

The members 1a, 2a and 3a of the stub section 14 may as shown in Fig. 8 pass parallel to each other straight across the fuselage. When the configuration of the wings demand various tapers as in the longitudinal direction of the wings the members 1, 2 and 3 can assure various angular relationships as shown in Figs. 11, 12 and 13 whilst the same method of strutting may be employed as shown. Where the stub end of a wing has a streamline merge into the fuselage body as indicated by the arcuate lines 36 in Figs. 9 and 10 the members 1a, 2a and 3a can extend parallel with each other across the fuselage frame, and one or more of them as for example 1a and 3a as shown in Fig. 9 can extend beyond the sides of the fuselage in the same parallel planes, the remainder as at 2a and extensions 2b suitably in-

clined and bolted, welded or otherwise suitably secured to the central part 2a. Still further all of the stub elements 1a, 2a and 3a can be with inclined parts connecting the wing spar elements to the parts of the stub section which extend across the fuselage as indicated at 1c, 2c in Fig. 10. The opposed ends of these relatively inclined parts of the spar elements 1, 2 and 3 and the stub elements can be hinged together as previously described by suitably inclining the forks 20 and lugs 19 of the hinges relatively to their plugs to maintain the forks and lugs in parallel planes to permit of hinging.

I claim:—

15. 1. A wing spar structure comprising three centre stub section tubular metal members secured across the frame of the fuselage parallel with each other, seating accommodation in the space between the said tubular members, a triangular section wing spar connected to each end of said stub section, tubular struts secured in sets of three across the said spar members, flattened ends to said struts, tubular lining members fitted at intervals inside the tubular spar members, boss like enlargements on said lining members, studs threaded into said enlargements and passing through said flattened ends of the said struts and nuts threaded on to said studs securing said struts to the tubular members.
20. 2. A main spar for an aeroplane wing comprising three longitudinal tubular members arranged to provide a triangular section spar, a series of sets of struts secured at intervals along the length of the spar, each set of struts being arranged so that it forms a substantially closed triangle round the three faces of the spar with the ends of the struts substantially normal to the longitudinal members, a plurality of substantially parallel diagonal stays at each face of the spar secured across adjacent struts at the diagonally opposite junctions of said adjacent struts to said longitudinal members, flattened ends to said struts and stays, studs passed through such flat-

tened ends into the said longitudinal members at the junction of the said struts and stays with said longitudinal members, and nut like enlargements inside said longitudinal members into which said studs are threaded.

3. A main spar for an aeroplane wing comprising three longitudinal tubular members arranged to provide a triangular section spar, a series of sets of tubular struts secured at intervals along the length of the spar, each set of said struts being arranged so that it forms a substantially closed triangle round the three faces of the spar with the ends of the struts substantially normal to said tubular longitudinal members, a plurality of substantially parallel diagonal tubular stays at each face of the spar each secured across a pair of adjacent struts at diagonally opposite junctions of said adjacent struts with said tubular longitudinal members, flattened ends to said tubular struts and stays, tubular lining members fitted at intervals inside said tubular longitudinal members, boss like enlargements on said lining members, studs threaded into said enlargements and passing through said flattened ends of said struts and stays, and nuts threaded on to said studs securing said struts and stays to said longitudinal tubular members.

4. In an aeroplane wing assembly a main spar composed of two sets of three longitudinal main tubular members arranged to obtain a triangular section, two of said members being located one substantially immediately above the other and in rear of the remaining tubular member, a correspondingly arranged set of three tubular members secured transversely across the fuselage frame, the said two sets of three longitudinal main tubular members extending in continuity with the said transverse members of the fuselage, the said rear pairs of said main members being hinged to the corresponding pair of the transverse members of the fuselage.

JAMES MARTIN.
